COMBUSTION ENGINE

Fritz Wehinger, Baden, Switzerland

Application March 23, 1937, Serial No. 132,564
In Germany March 28, 1936

3 Claims. (Cl. 74—60)

My invention relates to a wobble-plate which converts the reciprocatory movement of the pistons into a rotary motion of the shaft. The connection between the piston and the wobble plate is made by a slide, fitted to the pin of a 5 guidecase, connected to the piston.

Reference is to be had to the accompanying drawing in which,

Fig. 1 shows a section through the combustion engine,

Fig. 2 shows a section through the wobble plate and their connections,

Figs. 3 and 4 show the different sections of the connecting plate driven by the wobble plate,

Fig. 5 shows a partial section according to line I—I of Fig. 2.

Figs. 6 and 7 show the arrangement for changing the stroke.

According to Figs. 1 and 2 the wobble plate 22 is fixed to the shaft 26. The connecting plate 23 is placed around the wobble plate 22 and rests on ball bearings. The connecting plate 23 has slots 29, 30, 58, 82 which serve as guides for the slides 24, 25, 59, 85. The slides rest on the balls 28, 81, 57, 80 of the different pins 27, which are fastened to the guide cases 41, 42. The guide cases 41, 42 are connected to the pistons 2, 3, 4, 5 by the rods 54. The cylinders and their piston form the combustion chambers 6, 7, 8, 9, the chambers for the gas mixture 10, 11, 12, 13, the cleaning chambers 14, 15, 16, 17, 18, 19, 20, 21 for air. The cylinders are placed inside of the case 1.

The working of the wobble plate will be described according to Figs. 1—5.

The connecting plate 23, driven forward and backward by the explosions of the cylinders, makes the wobble plate 22 rotate. As the slide 25 is surrounded by the four walls of the slot 29 tightly and as the slide 25 is fixed to the case 42 which is guided in a straight line backward and forward, the upper part of the connecting plate 23 with the slot 29 makes also a straight motion backward and forward. But as known the parts of the connecting plate 23 with the slots 58 and 82 make also a forward and backward motion but at the same time they make a corresponding small upward and down motion. For instance any point of the part, which encloses the slot 58 describes the path of an eight (∞), going backward and forward. Therefore as the slides 59, 85 go backward and forward in a straight line, the slots 58, 82 must be open on two sides in relation to sufficient play for the slides 85, 59. Now it is a fact that all

slides are guided backward and forward in an exact straight line, also the upper part of the connecting plate 23 shows a straight motion, while the other parts make a combined motion. For instance the slot 58 moves somewhat up and down in direction of the arrows (Fig. 2), when going backward and forward, while the slide 85 moves backward and forward in a straight line. Therefore the slot 58 must be open on top and bottom. It is important that the connecting plate 23 does not show any movable connections, which could exert severe complicated accelerations of the weights in relation to the combined movement of the different parts.

Figs. 6 and 7 show the arrangement for changing the stroke.

If in Fig. 2 the pin of the ball 81 would be placed into the holes 83, the stroke of the piston would be increased and if the pin of the ball 81 would be placed into the holes 90, the stroke of 20 the pistons would be decreased. Instead of placing the pin of the ball 81 into the different holes 83, 90, the pin 86 of the ball 87, Fig. 6, carrying the slide 88, is fixed to the eccentric 84 with the shaft 89.

The eccentric 84, shown in the position of Fig. 6, exerts the same stroke as if the pin of ball 81 is placed into the holes 83, 90.

If the eccentric 84 is turned 180° and is kept in this position by an arrester, which is not 30 shown, the stroke would be decreased and it would be the same as if the pin of the ball 81 would be placed into the holes 90.

A larger stroke increases the compression and therefore the speed of the motor is increased 35 too. A smaller stroke decreases the compression and therefore the speed of the motor is decreased too.

I claim:

1. A wobble plate of a combustion engine, rotating inside of a connecting plate, which is free of any moving parts and which is fitted with slots, slides attached to balls, fitted to guide-cases, moved backward and forward in a straight line and which are connected to the pistons, the 45 slides fitted into the slots of the connecting plate.

2. A wobble plate of a combustion engine, rotating inside of a connecting plate, which is free of any moving parts and which is fitted with 50 slots, slides attached to balls, fitted to guide-cases, moved backward and forward in a straight line and which are connected to the pistons, the slides fitted into the slots of the connecting plate, one slide surrounded by four walls of the 55

corresponding slot of the connecting plate tightly, the other slots surrounded by only two walls of the corresponding slots of the connecting plate tightly.

- 5 3. A wabble plate of a combustion engine, rotating inside of a connecting plate, which is free of any moving parts and which is fitted with slots, slides attached to balls, fitted to guide-cases, moved backward and forward in a straight

line and which are connected to the pistons, the slides fitted into the slots of the connecting plate, one slide surrounded by four walls of the corresponding slot of the connecting plate tightly, the other slots surrounded by only two walls of the corresponding slots of the connecting plate tightly, a device arranged for shifting the slides for the purpose of changing the stroke. 5

FRITZ WEHINGER.
